DOUGHNUT TRANSPORTING TRAY

Thomas B. Brickson, Los Angeles, Calif., assignor, by mesne assignments, to Doughnut Corporation of America, New York, N. Y., a corporation of New York

Application May 23, 1947, Serial No. 139,232

Term of patent 14 years

(Cl. D44—10)

To all whom it may concern:

Be it known that I, Thomas B. Brickson, a citizen of the United States and residing at Los Angeles, in the county of Los Angeles, State of California, have invented a new, original, and ornamental Design for Doughnut Transporting Tray, of which the following is a specification, reference being had to the accompanying drawing, forming part thereof, in which:

Fig. 1 is a top plan view of a doughnut transporting tray, showing my new design.

Fig. 2 is an end elevation.

Fig. 3 is a top plan view of one section of the tray enlarged for the purpose of clear illustration of detail.

I claim:

The ornamental design for a doughnut transporting tray, substantially as shown.
